[57] CLAIM

The ornamental design for a flexible covering for partitions or the like, as shown and described.

DESCRIPTION

FIG. 1 is a front elevational view of a flexible covering for partitions or the like showing my new design;

FIG. 2 is a rear elevational view thereof;

FIG. 3 is a front perspective view thereof, shown applied to the convex surface of a partition;

FIG. 4 is a side elevational view taken from the right of FIG. 3;

FIG. 5 is a rear perspective view thereof, shown applied to the flat surface of a partition;

FIG. 6 is a rear perspective view thereof, shown applied to the convex surface of a partition.

The broken lines in FIGS. 3, 4, 5, and 6 are for illustrative purposes only, and disclose environmental applications of the design.
